UNITED STATES PATENT OFFICE.

CHARLES J. ALLEN, OF MOORESTOWN, NEW JERSEY.

DESIGN FOR A GEAR-CASING.

45,828.

Specification for Design.

Patented May 26, 1914.

Application filed January 19, 1914. Serial No. 813,114. Term of patent 7 years.

To all whom it may concern:

Be it known that I, CHARLES J. ALLEN, a citizen of the United States, and a resident of Moorestown, county of Burlington, and State of New Jersey, have invented a new, original, and ornamental Design for Gear-Casings, of which the following is a specification, reference being had to the illustrations shown in the accompanying drawing, wherein—

Figure 1 is a perspective view and Fig. 2 is a front elevational view.

What I claim is:

The ornamental design for gear casing substantially as shown.

CHARLES J. ALLEN.
